UNITED STATES PATENT OFFICE.

ARTHUR G. HATCH, OF DULUTH, MINNESOTA.

CONCRETE WALL.

Application filed October 11, 1922. Serial No. 593,717.

To all whom it may concern:

Be it known that I, ARTHUR G. HATCH, a citizen of the United States, residing at Duluth, in the county of St. Louis and State 5 of Minnesota, have invented certain new and useful Improvements in Concrete Walls, of which the following is a specification.

This invention relates to a new and improved concrete wall construction and more 10 particularly to a wall provided with securing or binding blocks which aid in maintaining the stability of the wall.

In certain types of concrete wall construction now in general use, the wall is formed 15 by oppositely faced blocks forming in effect two adjacent walls. In some such constructions, the walls are bonded by the engagement of integral flanges upon the blocks in opposed series. A wall of this character, 20 as generally designed and constructed, contains an excess of compressive strength over that normally required. This strength is due to the use of sufficient material to provide the necessary lateral stability in the 25 wall. In order to provide increased stability, it is desirable to place the adjacent walls at a greater distance apart, thus giving the wall a greater effective thickness. In such cases it is unnecessary to make the individual 30 blocks of greater thickness or to extend their flanges due to their excess of compressive strength. It is further undesirable to make different forms of blocks for walls of different thickness since this entails the duplication 35 of the necessary forms and apparatus used in making the blocks and a requirement for keeping a larger stock to include the various forms. It is also unnecessary to bond the walls by flanges throughout the length 40 of the block since adequate lateral bond can be secured by less material.

It is an object of the present invention to provide a wall construction having means adapted to secure and bind together adjacent walls.

It is a further object to provide a construction of this character adapted to be readily varied for walls of differing thickness.

50 It is also an object to provide securing means in such walls adapted also to form means for securing inner wall surfaces to the concrete wall.

Other and further objects will appear as 55 the description proceeds.

I have illustrated certain preferred embodiments of my invention in the accompanying drawings, in which—

Figure 1 is a plan view of a portion of the wall constructed according to the present invention;

Figure 2 is a section taken on line 2—2 of Figure 1;

Figure 3 is a view similar to Figure 1 showing a modified form of construction;

Figure 4 is an inner face view of the wall of Figure 3, the inner sheathing being removed;

Figure 5 is a view similar to Figure 1 showing a further modification;

Figure 6 is a view similar to Figure 1 showing a still further modification;

Figure 7 is an inner face view of Figure 6, the inner sheathing being removed;

Figure 8 is a section taken on line 8—8 of Figure 7.

Referring now to the form of construction shown in Figure 1, the wall comprises two adjacent walls A and B. These walls are composed of wall blocks 11 which, as shown in Figure 2, are formed upon their inner faces with recesses 12 formed by ribs 13 and flanges 14. As shown in Figure 1, the blocks forming the outer wall are provided with a plain face while those forming the inner wall are provided with the lugs or ribs 15 to which is secured the inner wall sheathing 16. The ends of the blocks are formed with the vertically extending recesses 17. The securing members 18 extend transversely between the walls A and B and bind them together. These members 18 are provided with edges 19 fitting within the recess formed by adjacent grooves 17. The members 18 are provided with longitudinally extending metal reinforcement 20.

In the form of construction shown in Figures 3 and 4, the wall consists of the opposed walls C and D. The outer wall is formed of blocks 21 having their ends formed with grooves 22, the grooves upon adjacent blocks together forming a recess having re-entrant angles. The blocks 23 forming the outer wall are shorter than the blocks 21, and their ends are spaced apart. The binding or securing blocks 24 are provided at one end with a dovetail portion 25 adapted to fit in the recess formed by the grooves 22. The opposite end of the blocks 24 extend through between adjacent ends of blocks 23. The

blocks 24 are provided with metal reinforcement ribs, as shown.

The blocks 23 are provided with ribs or lugs 27 adapted to bear against the inner wall sheathing and the blocks 24 preferably extend flush with the face of these ribs 27. The blocks 24 or the ribs 27 or both may be formed of nailable concrete so that the inner sheathing may be directly secured thereto.

The form of construction shown in Figure 5 is similar to that just described with the exception that the intermediate portion 30 of the securing blocks and the dovetail portion 31 of these blocks is reduced in thickness as shown in Figure 3. This reduces the size of the recess necessary in the outer wall blocks.

In the form of construction shown in Figures 6 to 8, the wall comprises two walls E and F. As best shown in Figure 8, the blocks 35 comprising the outer wall and blocks 36 comprising the inner wall are each provided with flanges upon their upper and lower sides which flanges differ in lateral extent. This permits a bond between walls to be secured by overlapping the flanges as clearly shown in Figure 8. In this construction the inner blocks 36 are of less length than the outer blocks 35 as shown in Figure 6. The securing blocks 37 are placed between the ends of adjacent blocks 36. These blocks 37 are preferably formed of nailable concrete and extend out beyond the face of blocks 36 and flush with the face of the ribs 38 carried by such blocks.

Obviously the forms of construction shown in Figures 1 to 5 permit walls to be made of differing thickness without variation in the size and construction of the wall blocks simply by varying the length of the transverse binding blocks. By placing these binding blocks as shown in Figures 3, 5 and 6 so as to extend beyond the wall face and serve as nailing supports for the inner wall sheathing, it becomes unnecessary to provide lugs upon the wall differing in material from the main body of the wall blocks. That is, the binding blocks may be made of nailable concrete while the wall blocks are entirely of other concrete. In such case the wall block ribs serve as spacing supports but will not receive any nails. The transverse binding blocks are provided with metal reinforcing which reinforcing

serves to take up the tensile stress and permit the blocks themselves to be of comparatively small area.

I have shown certain preferred embodiments of my invention but it is obviously capable of other and varied embodiments adapted for different purposes and constructions.

I claim:

1. Wall construction comprising adjacent walls formed of blocks and supplemental securing blocks extending between the adjacent walls and having portions extending beyond the wall face, said extending portions being formed of nailable concrete.

2. Wall construction comprising adjacent walls formed of blocks and supplemental securing blocks extending between the adjacent walls and having portions extending beyond the wall face, said securing blocks being further provided with portions extending within re-entrant angles upon the wall blocks whereby they secure the adjacent walls together.

3. Wall construction comprising adjacent walls formed of blocks and supplemental securing blocks connecting the adjacent walls, the securing blocks having portions fitting within the contour of one wall the end of the securing block being covered by the wall blocks, and having its opposite end extending through and beyond the other wall.

4. Wall construction comprising adjacent walls formed of blocks and supplemental securing blocks connecting the adjacent walls, the securing blocks having portions fitting within the contour of one wall the end of the securing block being covered by the wall blocks, and having its opposite end extending through and beyond the other wall, the extending portion being formed of nailable concrete.

5. Wall construction comprising adjacent walls formed of blocks and supplemental securing blocks connecting the adjacent walls, the securing blocks having dove tailed ends fitting within a similar recess formed in the ends of two adjacent blocks of one wall the end of the securing block being covered by the wall blocks, and having its opposite end extending through and beyond the other wall.

Signed at Duluth, Minnesota, this 30th day of September, 1922.

ARTHUR G. HATCH.
